US00D690295S

(12) **United States Design Patent**
Fletcher et al.

(10) **Patent No.:** **US D690,295 S**
(45) **Date of Patent:** **** Sep. 24, 2013**

(54) **INTERACTIVE INPUT SYSTEM
COMPONENT**

(71) Applicant: **SMART Technologies ULC**, Calgary (CA)

(72) Inventors: **Mark Andrew Fletcher**, Nepean (CA); **Alan Peter Boykiw**, Calgary (CA); **Cheng Guo**, Calgary (CA); **Paul Anthony Auger**, Osgoode (CA)

(73) Assignee: **SMART Technologies ULC** (CA)

(**) Term: **14 Years**

(21) Appl. No.: **29/440,302**

(22) Filed: **Dec. 20, 2012**

Related U.S. Application Data

(60) Continuation of application No. 29/408,920, filed on Dec. 19, 2011, now Pat. No. Des. 675,621, which is a division of application No. 29/363,312, filed on Jun. 8, 2010, now Pat. No. Des. 657,787.

(57) **CLAIM**

The ornamental design for an interactive input system component, as shown and described.

DESCRIPTION

FIG. 1 is front perspective view of the interactive input system component in accordance with our design;

FIG. 2 is a rear view of the interactive input system component of FIG. 1;

FIG. 3 is a first side view of the interactive input system component of FIG. 1;

FIG. 4 is a second side view of the interactive input system component of FIG. 1;

FIG. 5 is a front view of the interactive input system component of FIG. 1;

FIG. 6 is a top view of the interactive input system component of FIG. 1; and,

FIG. 7 is a bottom view of the interactive input system component of FIG. 1.
